(57) **CLAIM**

The ornamental design for a solar light for signs, as shown and described.

DESCRIPTION

FIG. 1 is a top perspective view of a solar light.

FIG. 2 is a top plan view of the solar light.

FIG. 3 is a front view of the solar light, the rear view being a mirror image thereof.

FIG. 4 is a left side view of the solar light, the right side view being a mirror image thereof.

FIG. 5 is a bottom plan view of the solar light.

FIG. 6 is a bottom perspective view of the solar light.

FIG. 7 is a top perspective view of the solar light installed on a sign; and,

FIG. 8 is a top perspective view of the solar light shown in conjunction with a partial sign.

The broken lines shown in the drawings illustrate a sign and form no part of the claimed design.
